Attorney—James H. Littlepage

ABSTRACT: A document sorting device comprising a plurality of document dividers each in the form of a sheet mounted on a pair of rollers which are trapped between a resilient upwardly urged base and a pair of spaced horizontal guide rails, the rollers being permanently attached to the dividers and being held in frictional engagement between the guide rails and the base by the spring member which urges the base upwardly.

1
DOCUMENT SORTING DEVICE

BACKGROUND OF THE INVENTION

It is known to provide a document sorting device in which each of the dividers is mounted on a pair of rollers which are trapped between a rigid base and a pair of spaced guide rails. In this known sorting device, the spacing between the dividers can only be varied by changing the rollers so as to provide rollers of a greater or smaller diameter and this necessitates altering the depth of the gap between the rails and the base. This known sorting device also has the disadvantage that, to ensure that the rollers can be readily changed they are a slide fit on to a rod attached to the divider and consequently are liable to drop off and become lost when the divider is removed from the device.

It is an object of the present invention to provide a sorting device in which each divider is mounted on rollers which are permanently attached to the divider and in which pressure is exerted on the rollers so as to maintain the rollers normally in a given position while allowing them to be moved manually into a new position to vary the spacing between the dividers. The present invention also provides spacing members for insertion between adjacent dividers to maintain a given spacing between the dividers.

STATEMENT OF THE INVENTION

A document sorting device comprising a frame having a pair of spaced horizontal guide rails, a pressure pad beneath the guide rail, which is spring urged upwardly towards the guide rails, and a plurality of document dividers each of which is mounted between the guide rails on a pair of free running rollers so as to be freely pivotable about the axis of the rollers, the rollers being trapped between the guide rails and the pressure pad and being normally held in position by the upward pressure of the pressure pad but movable to vary the spacing between the dividers by the application of a force sufficient to overcome the friction created on the rollers by the pressure pad.

DESCRIPTION OF THE DRAWINGS

FIG. 1 is a longitudinal section through a document sorting device according to the present invention.

FIG. 2 is a transverse section through the document sorting device of FIG. 1 taken on the line II-II of FIG. 1.

FIG. 3 is a plan view of a part of the document sorting device of FIGS. 1 and 2.

FIG. 4 is a plan view similar to FIG. 3 illustrating the manner in which the dividers of the document sorting device are inserted and removed from the frame.

FIG. 5 is a section through a detail of one of the dividers shown in FIGS. 1 to 3, and

FIG. 6 is an end view of the device shown in FIGS. 1 and 2.

DESCRIPTION OF THE PREFERRED EMBODIMENT

In FIGS. 1 to 4, a document sorting device is indicated generally at 10. The device 10 comprises a frame 11, a pressure pad 12 and a plurality of document dividers 13.

The frame 11 is formed from a sheet of any suitable material, for instance aluminum or a relatively rigid plastics and comprises a flat rectangular base 14, upstanding sidewalls 15 and 16 and upstanding end walls 17 and 18. The edge portions of the sidewalls 15 and 16 are flanged inwardly at 90° to form horizontal guide rails 19 and 20 respectively, which overlie the base 14.

The pressure pad 12 comprises an upper sheet 21 of relatively stiff material, for instance vulcanized fibre board backed by one or more cardboard sheets 21a which is trapped between the guide rails 19 and 20 and a pair of spring members in the form of resilient strips 22, 22a which can be formed from any resilient material such as rubber or a highly resilient synthetic plastics material. The resilient strips 22, 22a extend beneath the rails 19 and 20 and urge the sheet 21 upwardly

against the rails but the sheet 21 can be depressed manually away from the guide rails without undue difficulty. The resilient strips 22, 22a are supported on two further cardboard sheets 50, 51, and four rubber feet 52 are attached to the base 14 in any suitable and convenient manner.

The pressure pad 12 is assembled in the frame 11 by flexing the two cardboard sheets 50, 51 about their longitudinal axes and inserting them flat on the base 14 and beneath the rails 19 and 20. The two strips 22, 22a are then laid in place against the sidewalls 15 and 16 and beneath the rails 19 and 20 and finally the upper cardboard sheet or sheets 21a and the vulcanized fibre sheet 21 are flexed and inserted between the strips 22, 22a and the rails 19 and 20. The assembly of the frame 11 and pressure pad 12 is thus completed manually without the use of any screws, clips or bolts.

Each divider 13 comprises a relatively stiff sheet 23 of manilla, vulcanized fibre or other similar material having a rod 24 attached across its lower end with the aid of a metal clip 25 and a pair of rivets 26, 27. The rod 24 projects outwardly from the opposite sides of the sheet 23 and similar rollers 28, 29 are attached to the projecting ends of the rod 24. The rollers are trapped on the rod 24 by deforming the ends of the rod as at 30 and 31, but can rotate freely on the rod. The sheet 23 of each divider is clamped to its rod 24 and rotates with the rod.

Each divider 13 is mounted in the frame 11 by holding the rod 24 of the divider in a horizontal position between the guide rails 19 and 20, inclining the rod to the transverse axis of the guide rails, as shown in full line in FIG. 4, pressing the divider downwardly so as to depress the pressure pad 12 until the rollers 28 and 29 are located beneath the level of the rails 19 and 20 and rotating the divider about a vertical axis into the position shown in broken line in FIG. 4, with the rollers 28 and 29 trapped between the guide rails 19 and 20 respectively and the pressure pad 12.

The divider is then freely rotatable about the axis of the rollers and normally held in its axial position, but can be moved lengthwise of the rails 19 and 20 if sufficient force is exerted upon it to overcome the friction exerted on the rollers 28, 29 by the pressure pad 12.

In order to complete the assembly of the device 10 a pair of end plates 32 and 33 and a pair of handles 34 and 35 are also mounted between the rails 19 and 20.

Each end plate 32 and 33 respectively comprises a sheet of stiff material, for instance a suitable metal mounted on a rod 24 and rollers 28 and 29 in a similar manner to the dividers 13. Each end plate is also provided with locking means in the form of an L-shaped lug 36 and 37 respectively which is welded or otherwise attached to the outside surface of its respective plate.

Each handle 34 and 35 respectively comprises a U-shaped rod having outwardly directed end portions 38 which are located in end pieces 39, which are trapped between the pressure pad and the guide rails 19 and 20 respectively.

As can be seen from FIG. 6, each end plate 32 and 33 respectively can be locked in a vertical position by trapping a portion of the adjacent handle, 34 or 35 respectively, beneath the L-shaped lug on the end plate so that the end plate forms a vertical end stop and support for the dividers 13.

In use, documents to be sorted are inserted in the gaps between the dividers 13, each of which can carry, on its upper edge, suitable index markings or identification strips. It will be appreciated that the number of documents inserted behind some of the dividers will be greater than the number of documents inserted behind others and consequently a variable spacing between the dividers 13 will often be required. This variable spacing is achieved quickly and easily by depressing a given divider, to release the rollers, moving the divider into its new position and releasing it so that it is again urged upwardly by the pressure pad 12 against the guide rails 19 and 20 and clamped in its new position. In order to ensure that the new space between adjacent rollers is maintained, a flexible spacer strip 40 is inserted between the adjacent dividers. The flexible spacer strip 40 is formed from any suitable material such as a

synthetic plastics or rubber and is of approximately the same depth as the diameter of the rollers 28, 29. It is of slightly greater length than the gap between the guide rails 19 and 20 and is flexed and then inserted beneath the guide rails so that its end portions are trapped between the guide rails and the pressure pad. A plurality of spacers 40, 40a are provided with the device device 10, the spacers 40, 40a being of different widths so that the appropriate width sa spacer 40 can be selected to meet any given requirement.

It will be appreciated that spacers 40 will normally be inserted wherever necessary between the dividers and between each end plate and the adjacent handle so that there is no free space along the length of the guide rails. This ensures that the spacing between adjacent dividers cannot be altered accidentally and if a divider has to be removed or a new divider inserted, a spacer 40 is first removed to allow sufficient room for a divider 13 to be inclined to the transverse axes of the guide rails so that it can be removed or inserted.

The spacers 40 exert a pressure on the base of the dividers which serves to retain the dividers in their angular positions against accidental rotation, although each of the dividers 13 is freely rotatable relative to its rollers and can thus be manually moved through an angle of approximately 130°—140° to facilitate the insertion and removal of documents.

It will be appreciated that any suitable spring means can be provided to exert the upward pressure on the sheet 21 of the pressure pad 12 and that the structure of the frame 11 can be varied to suit manufacturing or operating requirements.

Further minor modifications can be made to the above described embodiment without departing from the spirit and scope of the invention which is best described in the following claims.

We claim:

1. A document sorting device comprising a frame having a pair of spaced horizontal guide rails, a pressure pad beneath the guide rail, which is spring urged upwardly towards the guide rails, and a plurality of document dividers each of which is mounted between the guide rails on a pair of free running rollers, the rollers being trapped between the guide rails and the pressure pad and being normally held in position by the upward pressure of the pressure pad but movable to vary the spacing between the dividers by the application of a force sufficient to

overcome the friction created on the rollers by the pressure pad.

2. A device as claimed in claim 1, wherein the said rollers of each divider are permanently attached to the divider.

3. A device as claimed in claim 2, wherein each divider comprises a sheet of stiff material mounted nonrotatably on a rod having end portions which project from opposite sides of the sheet, the said rollers being permanently mounted, for free running, on the projecting end portions of the rod.

10 4. The combination of a device as claimed in claim 1 and a plurality of spacers each of which comprises a resilient strip of material, the depth of which is approximately equal to or slightly less than the diameter of the rollers and the length of which is greater than the gap between the guide rails, each spacer having its opposite ends trapped beneath the guide rails to space the adjacent dividers apart.

5 5. A device as claimed in claim 1, wherein the pressure pad comprises a sheet of stiff material and a spring member or members located beneath the sheet to urge the sheet upwardly.

15 6. A device as claimed in claim 5, wherein the frame and guide rails are formed integrally from a single sheet of material the edge portions of which are bent upwardly and inwardly to form the guide rails.

25 7. A device as claimed in claim 6, wherein a pair of end plates are mounted between the guide rails on free running rollers which are trapped between the guide rails and the pressure pad and wherein a pair of handles are pivoted to the ends of the frame, each of the end plates being provided with a locking means which is engageable with the adjacent handle to lock the end plate in an approximately vertical position.

30 8. A device as claimed in claim 7, wherein each handle comprises a looped rod and the locking means on each end plate comprises an L-shaped lug adapted to trap a portion of the adjacent handle against the outer surface of the end plate.

35 9. The combination of a device as claimed in claim 8 and a plurality of spacers each of which comprises a resilient strip of material, the depth of which is approximately equal to or slightly less than the diameter of the rollers and the length of which is greater than the gap between the guide rails, each spacer having its opposite ends trapped beneath the guide rails to space the adjacent dividers apart.
